(57) CLAIM

The ornamental design for a clamp as shown and described.

DESCRIPTION

FIG. 1 is a top perspective view of a clamp showing our new design;

FIG. 2 is a bottom perspective view thereof;

FIG. 3 is a top plan view thereof;

FIG. 4 is a bottom plan view thereof;

FIG. 5 is a first side view thereof; and,

FIG. 6 is a second side view thereof.

The broken lines in the drawings are included to show portions of the clamp that form no part of the claimed design.
